UNITED STATES PATENT OFFICE.

BENJAMIN C. WAITE, OF BROOKLYN, NEW YORK.

MACHINE FOR CUTTING, SANDING, AND ROLLING ROOFING-FELT.

SPECIFICATION forming part of Letters Patent No. 380,065, dated March 27, 1883.

Application filed June 30, 1887. Serial No. 242,988. (No model.)

To all whom it may concern:

Be it known that I, BENJAMIN C. WAITE, of the city of Brooklyn, in the county of Kings and State of New York, have invented certain 5 new and useful Improvements in Machines for Cutting, Sanding, and Rolling Roofing-Felt, of which the following is a full, clear, and exact description.

Reference is to be had to the accompanying 10 drawings, forming a part of this specification, in which similar letters of reference indicate corresponding parts in all the figures.

Figure 1, Sheet 1, is a side elevation of my 15 improvement, partly in section. Fig. 2, Sheet 1, is a front view, partly in section, of the sanding-hopper and its attachments. Fig. 3, Sheet 2, is a sectional elevation of the improvement, taken through the line $u-u$ of Fig. 1, parts being broken away. Fig. 4, Sheet 20 2, is a sectional side elevation of the knife-driving mechanism, taken through the line $x-x$, Fig. 3, looking toward the left. Fig. 5, Sheet 2, is the same section as Fig. 4, but looking to the right. Fig. 6, Sheet 2, is a sectional elevation of the same, taken through the line $y-y$, Fig. 3. Fig. 7, Sheet 2, is a side elevation of the felt-receiving mandrel. Fig. 8, Sheet 2, is a cross-section of the same, taken through the line $z-z$, Fig. 7.

30 The object of this invention is to facilitate the cutting, sanding, and rolling of roofing-felt.

The invention consists in the machine for cutting, sanding, and rolling felt, constructed and operating as hereinafter described; in a 35 mechanism whereby the knife will be operated with a quick downward movement and a slow upward movement; and in a peculiarly-constructed mandrel arranged so that the felt will be wound automatically and the felt roll can 40 be readily removed from the machine.

The invention also consists in a suspended sand-hopper and a mechanism by which the amount of sand discharged can be regulated, and in the construction and arrangement of 45 parts and details, as will be hereinafter more specifically set forth and claimed.

A is the frame of the machine, to the top of the rear end of which are attached two slotted standards, B, to receive the journals of the 50 two rolls C C', or the bearings in which the said journals revolve. The lower roll, C', is grooved, as at D', to receive a number of belts, D, so

that the upper roll, C, will not rest upon the said belts D. The belts D also pass around a roll, E, journaled in the middle part of the 55 frame A, so as to support the felt as it is drawn from the machine in which it is prepared and fed forward by the rolls C C'. The journals of the rolls C C' are connected by gear-wheels F, so that they will revolve at the 60 same speed. To one of the journals of the lower roll, C', is attached a crank-arm, H, which is slotted to receive the crank-pin I, so that the said crank-pin can be adjusted to regulate the throw of the rod J, pivoted 65 to the said crank-pin, as may be required. The other end of the connecting-rod J is pivoted to the pawl K, which engages with the teeth of the ratchet-wheel L. The pawl K is pivoted to and supported by two bars, M, the 70 lower ends of which have holes formed through them to receive and ride upon the hub of the ratchet-wheel L, which wheel is placed loosely upon the shaft N, journaled in the lower part of the frame A, and is kept from being turned 75 back by the friction of the pawl K, in its rearward movements, by a friction-brake formed of two bars, O, placed above and below one end of the hub of the said ratchet-wheel L, connected at one end by a bolt, P, and connected at the other end and held in place by a standard, Q, attached to the floor or the base of the frame A and having upon its upper end a screw-thread and a hand-nut, R, so that the friction applied by the said brake can be 80 readily regulated as may be required. To the other end of the hub of the ratchet-wheel L is attached, or upon it is formed, a crank-arm, S, the crank-pin s' of which engages with the crank-pin t' of a crank-arm, T, keyed or otherwise secured to the shaft N. To the ends of the shaft N are attached crank-arms U, to which are pivoted the lower ends of the connecting-rods V. The upper ends of the connecting-rods V are pivoted to the ends of a 90 cross-head, W, which slides up and down in slotted standards X, attached to the middle part of the frame A. Upon the ends of the cross-head W, or upon sliding cross-bars or bearings Y, attached to the said ends, and 95 which slide upon the standards X, rest spiral or other shaped springs Z, the upper ends of which rest against the caps a, attached to the upper ends of the slotted standards X, and

said springs are kept in place by guide-rods *b*, attached to the cross-head *W* and passing through guide-holes in the said caps *a*.

To the cross-head *W* is attached the upper 5 knife, *c*, the edge of which is beveled and is inclined from the center toward each end, as shown in Fig. 3.

d is the lower knife, which has a straight beveled edge and is attached to a cross-bar, *e*, 10 secured to the frame *A* a little in front of the roll *E*, and in such a position that the straight side of the knife *c*, in its downward movement, will move along the straight side of the knife *d*, so that the felt will be cut with a shear cut.

15 Each of the connecting-rods *V* is made in two parts connected at their adjacent ends by a long right-and-left nut, *f*, or other suitable coupling, so that the said rods *V* can be readily shortened as the knives *c d* wear in use.

20 To the shaft *N* is attached a fly-wheel, *g*, to give momentum to the said shaft, and a ratchet-wheel, *h*, with the teeth of which engages the pawl *i*, pivoted to the frame *A*.

As the pawl *K* is operated by the revolution 25 of the roller *C*, it turns the ratchet-wheel *L*, bringing the crank *S* into contact with the crank *T* and turning the shaft *N* until the crank *U* and knife *c* have reached the upper points of their movements.

30 As the crank *U* passes the upper point of its movement, the weight of the connecting-rods *V*, the momentum of the fly-wheel *g*, and the elasticity of the springs *Z* force the knife *c* downward, cutting the felt and turning the shaft *N* until the crank *U* has been carried past the lowest point of its movement and the knife *c* has been raised out of contact with the felt, the said shaft being held from being turned back by the ratchet-wheel *h* and pawl *i*. The shaft *N* and

35 knife *c* remain stationary until the regular advance of the ratchet-wheel *L* brings the crank *S* again into contact with the crank *T*, and the knife *c* is again raised for another cut.

To the frame *A*, a little in advance of the 40 knife *d*, is journaled a roll, *j*, around which pass a number of belts, *k*. The belts *k* also pass around a roll, *l*, journaled to the forward end of the frame *A*. To the journal of the roll *l*, or to a journal of one of the rolls, *C*, is at-

45 tached a pulley, *m*, to receive a driving-belt, *n*, to which motion may be given from any convenient power. To a journal of the roll *l* is attached a fast and a loose pulley, *o*, around which passes a belt, *p*. The belt *p* also passes 50 around the pulley *G*, attached to one of the rolls, *C*.

The roll *L* is made larger than the roll *C*, or the pulley *o* is made larger than the pulley *G*, so that the belts *k* will travel faster than the 55 belts *D* and will roll up the felt after it is cut by the knives *c d* faster than it is fed to the machine and form a space between the rear end of the piece being rolled and the forward end of the following piece, to give the operator time to remove the roll of felt and replace the mandrel.

To the forward end of the frame *A*, or to the bearings for the roll *l*, are attached standards *q*, which are slotted to receive the journals of the mandrel *r*, and are inclined forward, so that 70 the roll of felt can be readily removed and the mandrel replaced.

The body of the mandrel *r* is made in two parts or halves, the forward end of each part entering a socketed band, *s*, attached to or 75 formed upon each part at the inner end of its journal.

The adjacent faces of the parts of the mandrel *r* are beveled from the center toward each edge, so as to form, when the two parts are 80 placed together, wedge-shaped openings, as shown in Fig. 8, into which the end of the felt can be readily inserted when starting the roll. After the roll is started the winding will be continued by the movement of the roll *l*. 85

The mandrel *r* is placed in the slotted standards *q*, and when the end of the felt reaches the roll *l* it is inserted in the opening between the parts of the said mandrel and the said mandrel is turned to begin the winding. The winding 90 is then continued by the action of the roll *l*.

As the felt passes to the roll *l*, it is sprinkled with sand or other desired material from the hopper *t*. The hopper *t* is formed with vertical ends and inclined sides, is suspended by 95 jointed bars *u* from the ceiling of the room or other suitable support, and has a long narrow opening, *v*, in its lower part, so that the sand will be discharged in a thin sheet. The size of the discharge-opening and the quantity of 100 sand discharged are regulated by a slide, *w*, to which are hinged the lower ends of two or more bars, *x*. The upper ends of the bars *x* are pivoted to cranks formed upon the shaft *y*, journaled in bearings in the upper part of one 105 end of the hopper *t* and having a hand-wheel, *z*, attached to a projecting end for convenience in turning it to adjust the slide *w*. The slide *w* is locked in place when adjusted by a hand-nut, *1*, screwed upon the crank-shaft *y*. 110

To one side of the hopper *t* is hinged the lower end of a connecting-bar, *2*, the other end of which is hinged to the crank-pin *3*, attached to the side of the pulley *4*, journaled in brackets *5*, attached to the ceiling or other suitable 115 support. To the shaft *6* is attached a pulley, *7*, to receive a belt, so that it can be driven from any convenient power to shake the hopper *t*, and thus insure a continuous discharge of sand. 120

Having thus described my invention, what I claim as new, and desire to secure by Letters Patent, is—

1. A machine for cutting, sanding, and rolling felt, consisting of the following elements 125 combined for operation substantially as set forth—viz., a feeding-belt, knives for severing the felt as it leaves said belt, delivery-belts moving at a quicker speed than the feeding-belt, a revoluble mandrel receiving the felt 130 from the delivery-belt, and a sanding-hopper.

2. In a felt-cutting machine, the combina-

tion, with a feeding-belt and a delivery-belt moving at a greater speed than the feeding-belt, and a fixed knife located between said belts, of a reciprocating knife having a slow upward movement and a quick downward movement, and an operating mechanism, substantially as shown and described.

3. In a felt-cutting machine, the combination, with a fixed knife, of a reciprocating 10 knife, a crank-shaft carrying a fixed ratchet, a pawl engaging said ratchet, connections between said crank-shaft and the reciprocating knife, and connections, substantially as set forth, between said shaft and a moving part of 15 the machine, whereby said shaft is advanced until the crank-pins are carried beyond their uppermost points of movement, as set forth.

4. In a felt-cutting machine, the combination, with a fixed knife, of a reciprocating 20 knife, a shaft carrying a fixed ratchet, a second ratchet loosely mounted on said shaft, a pawl engaging said loose ratchet, a reciprocating bar engaging said pawl, an arm fixed to said shaft, and an arm carried by said second 25 ratchet and engaging said shaft-arm, and connections between said shaft and said reciprocating knife, substantially as set forth.

5. In a machine for cutting, sanding, and rolling roofing-felt, the combination, with the rolls C C' and belts D, the movable knife c and 30 its cross-head W, of the springs Z, the connecting-bars J V, the ratchet-wheels L h and pawls K i, the cranks H S T U, and the fly-wheel g, substantially as herein shown and described.

6. In a machine for cutting, sanding, and rolling roofing-felt, the combination, with the sand-hopper t, of the jointed supporting-bars u, the hinged connecting-bar 2, and the crank-pulley 4, substantially as herein shown and 40 described, whereby the said hopper will be shaken, as set forth.

7. In a machine for cutting, sanding, and rolling felt, the combination, with the hopper t, of the slide w, the hinged connecting-bars x, the crank-shaft y, the hand-wheel z, and the hand-nut 1, substantially as herein 45 shown and described.
